CLAIM

The ornamental design for a "guide rail device", as shown and described.

DESCRIPTION

FIG. 1 shows a perspective view of the present design; FIG. 2 shows a front elevational view of the present design; FIG. 3 shows a rear elevational view of the present design; FIG. 4 shows a left elevational view of the present design; FIG. 5 shows a right elevational view of the present design; FIG. 6 shows a top plan view of the present design; FIG. 7 shows a bottom plan view of the present design; and, FIG. 8 is a front view showing the guide members of the present invention which have relocated to two sides. The guide rail device has been broken near the ends to disclose indefinite length.
